UNITED STATES PATENT OFFICE.

CHESSLY DEMPSEY, OF ADA, OKLAHOMA.

CUFF.

1,241,936.

Specification of Letters Patent.

Patented Oct. 2, 1917.

Application filed December 8, 1915. Serial No. 65,821.

To all whom it may concern:

Be it known that I, CHESSLY DEMPSEY, a citizen of the United States, residing at Ada, in the county of Pontotoc and State of Oklahoma, have invented new and useful Improvements in Cuffs, of which the following is a specification.

This invention contemplates the provision of a cuff or cuff band of novel construction, whereby provision is made for securing together the opposite ends of the cuff without necessitating the use of cuff links or analogous fastening elements.

More specifically stated, the invention aims to provide a cuff having a tab carried by one end thereof for engagement with the opposite end of the cuff in a manner to hold said ends together, the tab being associated with the cuff in a manner whereby the same can be arranged so as not to interfere with the use of cuff links or the like should their use be desired.

The nature and advantages of the invention will be better understood from the following description when considered in connection with the accompanying drawing, the invention residing in the specific construction, combination and arrangement of parts as claimed.

In the drawing forming part of this specification like numerals of reference indicate similar parts in the several views and wherein:

Figure 1 is a plan view of the cuff opened.

Fig. 2 is a similar view of the cuff closed showing the operative arrangement of the securing tab.

Fig. 3 is a sectional view taken on line 3-3 of Fig. 2.

Fig. 4 is a sectional view through the cuff, showing the inoperative position of the securing tabs.

In carrying out my invention I provide a cuff 5, with a tab 6 projecting centrally from the outer end of the cuff. The tab is adapted to be extended between the side portions of the cuff and passed through a transverse opening 7 adjacent the opposite end of the cuff. The tab is cut away to provide a

tongue 8 extending in an opposite direction 50 with respect to the tab, and adapted when the tab is passed through the slot 7 to engage one edge of said slot thereby effectively holding the cuff in position about the wrist. It is to be understood that the tab as shown 55 in this embodiment of the invention is constructed from the same material from which the cuff is made, and thereby forms an integral part, so that when the cuff is laundered and starched, the tab 6 will be rendered sufficiently stiff or rigid to facilitate its association with the free end of the cuff, and furthermore effectively holds the opposite ends of the cuff securely fastened. With 60 a cuff of this character it will be manifest that use of cuff links or the like is not necessary, thereby eliminating considerable inconvenience and expense as the result of the loss of such fastening elements. However to provide for the use of such fastening elements, should their use be desired, I 65 provide the tab 6 with a button hole 9 which registers with the usual button holes 10 in the opposite ends of the cuff. It is of course to be understood that when cuff links are 70 used, the tab is positioned between the side portions of the cuff, but not inserted through the slot 7.

While it is believed that the nature and advantages of the invention will be readily 80 apparent from the foregoing description, I desire to have it understood that I do not limit myself to the exact construction and arrangement herein shown, as the same is merely illustrative of one embodiment of the 85 invention and that such changes may be resorted to when desired as fall within the scope of the appended claims.

What is claimed is:

1. A cuff having button holes in both ends 90 thereof, one end of the cuff being also provided with a transverse slot, a flexible tab projecting centrally from the opposite end of the cuff to be received by said slot, or adapted to be folded between said ends, and 95 provided with a button hole adapted to align with the button holes of said cuff.
2. A cuff having button holes adjacent

both ends, and a transverse slot adjacent one end, a flexible tab projecting from the opposite end of the cuff and adapted to be passed through said slot when used, a tongue cut from said tab to engage the wall of said slot to hold the article in cuff form, and said tab being also foldable between the ends of the cuff and having a slot registering with

said button holes of the cuff for the purpose set forth.

In testimony whereof I affix my signature in presence of two witnesses.

10 CHESSLY DEMPSEY.

Witnesses:

A. H. CONSTANT,
Mrs. C. DEMPSEY.
